UNITED STATES PATENT OFFICE.

PAUL STEWART PITTINGER, OF PHILADELPHIA, PENNSYLVANIA, ASSIGNOR TO H. K. MULFORD COMPANY, OF PHILADELPHIA, PENNSYLVANIA, A CORPORATION OF PENNSYLVANIA.

MEDICINAL PACKAGE.

Application filed December 2, 1920. Serial No. 427,733.

To all whom it may concern:

Be it known that I, PAUL S. PITTINGER, a citizen of the United States, residing in Philadelphia, Pennsylvania, have invented 5 Medicinal Packages, of which the following is a specification.

In making tests to ascertain the susceptibility of a patient to the proteins known to cause various painful or distressing 10 symptoms such as those of hay fever, rose cold, or the like, it is customary to note the skin reactions occurring when a small quantity of each of several proteins is applied to the previously scarified skin surface;—there being a peculiar and characteristic 15 inflammation which occurs if the patient is susceptible to its action, within a definite time after the protein has been administered.

20 One object of the present invention therefore, is to provide a convenient package for holding a small amount of a protein, together with a scarifying needle for use in conveniently and quickly carrying out the 25 above tests;—it being particularly desired that said package shall be of such a nature as will contain a relatively minute quantity of the protein, such as will be sufficient for a single test, and which by virtue of its in- 30 expensive nature may be discarded after use.

These objects and other advantageous ends I attain as hereinafter set forth, reference being had to the accompanying drawings, in which,

35 Fig. 1 is a longitudinal vertical section on an enlarged scale, illustrating a medicinal package constructed in accordance with my invention;

40 Figs. 2 and 3 are longitudinal sections similar to Fig. 1, illustrating modified forms of the invention; and

Fig. 4 is a longitudinal section of a glass tube from which one form of my package may be conveniently made.

45 In Fig. 4 of the above drawings, 1 represents a suitable length of glass tubing, which in a typical case, is about two inches long and has through it a passage in the neighborhood of one thirty-second to one-six- 50 teenth of an inch in diameter.

To prepare this tube for use I heat it in a suitable flame at a point near one end until it has so far softened that its walls come together for a short length and close off the

passage 2 by a solid barrier 3, thereby di- 55 viding said passage into two chambers 4 and 5 of which the first is relatively short and of small capacity and the second is com- paratively long.

I then insert in the latter or longer cham- 60 ber 5 a scarifier preferably in the form of an ordinary pointed sewing needle 6 having ad- jacent its blunt end a flattened portion such as is formed in connection with the custom- 65 ary thread eye 7. The open end of the large chamber 5 is now heated in a suitable gas flame so that it is sealed as indicated at 8 and at any suitable stage in the oper- 70 ation, the tube is nicked at 9 by means of a file, preferably at a point about the middle of the length of the chamber 5.

The tube with its contained needle is then placed in a heating device where its temper- 75 ature is raised to such a point as to sterilize the two chambers 4 and 5 as well as the 80 needle 6, after which the small chamber 4 is filled with the protein desired and a soft rubber cap 10 is applied so as to tightly close the otherwise open end of said filled chamber. The package is now ready for 85 use, and it may be stored or safely trans- 90 ported without deterioration.

When desired for use, the tube is broken by being bent adjacent its middle and the 95 break naturally occurs at the nicked point 90 9. The sterile needle 6 is then used for scarifying a previously sterilized skin area to which the test is to be applied and there- 100 after is employed as a spoon or spatula for transferring a minute quantity of the pro- 95 tein from the chamber 4 to the scarified area. For this purpose the cap 10 is removed and the blunt end of the needle is inserted in said protein which is usually in the form of a powder, whereupon a small quantity of 105 the latter enters and is retained by the eye or flattened portion of the needle from which it may be delivered as desired to the scarified area. The package as a whole may thereupon be discarded, since it will be un- 110 derstood that it is not desirable that the scarifying point be used again or that other quantities of the protein be further em- 115 ployed.

If desired, in place of employing an 105 elongated tube of glass, I may substitute for this a suitable length of solid glass rod 11 and form in one end thereof a small cavity

4 for holding the desired small amount of protein. As before, this tubular chamber or recess may be made in any suitable manner and when filled with the protein is closed by 5 a rubber or other suitable cap or closure 10. The opposite end of the rod 11 in this form of my invention has fixed in it a steel scarifying needle or point 12, although if desired it may be drawn out into a sharp scarifying point 13 as shown in Fig. 3.

In any case however, the package itself carries a scarifying point and is also provided with a chamber of relatively minute capacity for containing the small amount 15 of protein required for a single test. Obviously other materials besides proteins may be placed in the chamber 4 and while for the purpose of making the tests above noted, said chamber is of relatively small capacity, 20 it may be made larger and employed to con-

tain vaccine, serum and other substances without departing from my invention.

I claim:

1. The combination of a tubular body of glass having two chambers; a needle sealed 25 in one chamber and having a substance receiving portion; a substance to be administered within the other chamber; with means for closing said second chamber.

2. The combination of a tubular body of glass having its walls fused together immediately adjacent one end to provide two chambers of which one is of relatively small capacity; a cap removably closing said latter chamber; a substance to be administered 35 within the smaller chamber; and a sterile needle hermetically sealed within the larger chamber.

PAUL STEWART PITTINGER.
